UNITED STATES PATENT OFFICE.

JACOB RIBAYSEN, OF CHICAGO, ILLINOIS.

DESIGN FOR A TOP PIECE FOR LIGHTING FIXTURES.

Application filed January 2, 1923. Serial No. 4,801. Term of patent $3\frac{1}{2}$ years.

To all whom it may concern:

Be it known that I, JACOB RIBAYSEN, a citizen of Russia, residing at Chicago, in the county of Cook and State of Illinois, have invented a new, original, and ornamental Design for Top Pieces for Lighting Fixtures, of which the following is a specification, reference being had to the accompanying drawing, forming part thereof.

The figure is a front view of a top piece for lighting fixtures, showing my new design.

I claim:

The ornamental design for a top piece for lighting fixtures, as shown.

In witness whereof I affix my signature.

JACOB RIBAYSEN.
